MANUFACTURE OF ARTIFICIAL FIBERS FOR SPINNING

Johannes Kleine, Dessau, Walther Zetzsche, Premnitz, and Paul Saffert, Bitterfeld, Germany, assignors to I. G. Farbenindustrie Aktiengesellschaft, Frankfort - on - the - Main, Germany

Application November 13, 1935, Serial No. 49,536
In Germany November 14, 1934

3 Claims. (Cl. 18—8)

Our present invention relates to an apparatus for the production of curled rayon staple fibers.

An object of the invention is the provision of an apparatus reducing substantially the required space to satisfy the great demand which has sprung up within the last few years in factories making artificial spinning fibers when operating according to the methods described in U. S. Patent No. 1,971,627 or French Patent 625,049.

10 Still another object is the saving of large quantities of liquids required for the spinning baths and for after-treatment.

Still another object is an apparatus for preparing artificial spinning fibers which have already been cut or torn to a desired length, and to ensure that they may be in a condition for direct manufacture to textiles without the introduction of a separate crimping operation.

Further objects will be seen from the detailed specification following hereinafter. Reference is made to the accompanying drawings in which

Fig. 1 shows diagrammatically a device for manufacturing artificial spinning fibers according to this invention,

25 Fig. 2 shows diagrammatically a modified device for manufacturing artificial silk according to this invention,

Fig. 3 shows diagrammatically a further modification of a device according to this invention,

30 Fig. 4 shows an arrangement for pressing a sliver according to this invention with a channel under the rollers for guiding away the liquid and roof-shaped pieces of sheet metal for leading away the liquid flowing through the perforated conveyer band,

35 Fig. 5 shows the manner in which the sliver is lifted from the conveyer band,

Fig. 6 shows a further modification of a device according to this invention,

40 Fig. 7 shows a roller provided with bosses for imparting a profile to the sliver,

Fig. 8 shows the arrangement of tubes near a guiding roller for treating the under side of the sliver, and

45 Fig. 9 shows the arrangement of a driven perforated hollow roller over which the sliver passes and a tube arranged inside the roller for spraying liquid against the under side of the sliver.

We have found that artificial spinning fibers 50 which have already been cut in an operation performed directly behind the precipitating bath or after the threads have been partly or completely deacidified, and which then have been subjected to the chemical or other after-treatment, in the form of a sliver, exhibit a remarkably good ca-

pacity for being spun, in particular a stable crimping and good mechanical properties. It was not to be anticipated that the process of the invention would yield a wavy thread exhibiting when spun a good adhesion between the individual fibriles without a separate operation for producing the crimping necessary for the further working up into textiles. An especially good crimping effect is obtained when viscose rayon fibers are cut, while still in acid condition or preferably while the thread is only freshly coagulated and not yet decomposed, then loosened by a suitable watering device and in this condition, subdivided as uniformly as possible, brought to the chemical after-treatment and purification on conveying devices, on which the whole of the after-treatment may occur.

The endless fiber band coming from the spinning nozzles is cut before or after having been deacidified and floated with water through a loosening device on a perforated conveyer band. The fibers are deposited on this conveyer band in the form of a sliver. In this form the fibers are subjected to the complete after-treatment by irrigation. The conveyer bands must be resistant to the chemicals with which they come into contact; a perforated band of rubber or resistant sheet metal may be used or a band of wire gauze or of a textile material may be suitable. One single conveyer band of sufficient length may be used 30 or separate conveyer bands may be used for each different treatment. The irrigation is produced by the known spraying apparatus and is effected over such a length of the conveyer band that the treatment is complete throughout the sliver. 35 Between the different treatments the sliver is squeezed by means of squeezing rollers. The liquid after passing through the sliver flows through the perforated conveyer band and is collected. Suitable devices may be arranged between the 40 upper and the lower part of the fiber band in order to protect the lower part of the conveyer band from the action of the liquids so that the action of the liquids on the band is reduced to the absolute necessary. The arrangement of a 45 trough at the place where the fibers are floated on the band for collecting the floating water is of particular importance since the large quantities of water would exert a strong mechanical and chemical strain on the lower part of the band. In the case of acid liquid the collecting of the liquid is still more important because of its deleterious chemical influence. If the conveyer band is subdivided it is preferably arranged so that the sliver is guided upwards to the squeezing roll- 50

55

- ers and after having passed the squeezing rollers it is guided downwards if desired by means of a short conveyer band, whereupon it is again guided upwards for the next treatment. In order to 5 spare the conveyer band the squeezing rollers may be arranged above the conveyer band and the sliver is lifted from it and thus guided to the squeezing rollers. After being squeezed the sliver again falls back on the conveyer band.
- 10 This involves the advantage that the liquid retained in the perforated conveyer band by capillary forces is not sucked back into the sliver. In order to promote the treatment a pair of squeezing rollers may be arranged in the middle of the 15 length over which one treatment lasts.

In order to promote the treatment in the lower layers of the sliver the lower roller of the pair of squeezing rollers may be grooved whereby the band is made thinner. This furthermore involves the advantage that the liquid more easily 20 flows off. For the same purpose of facilitating the treatment of the lower layers with the treating liquid a roller provided with bosses may operate against one of the rollers supporting the 25 conveyer band and thus imparts to the sliver passing between the two rollers a profile. In order to increase the washing effect the sliver may also be passed over a driven perforated hollow roller. In the interior of the hollow roller a 30 spraying device is arranged for spraying liquid against the under side of the sliver which passes over the hollow roller.

The accompanying diagrams illustrate the kind of apparatus in which the process can be 35 applied.

Referring to Fig. 1, the freshly produced band *a*, consisting of endless individual fibers, is cut or torn, while still in fresh condition, in a device marked *b* and is brought over a bridge piece, for 40 example a moistening trough *c*, to a watering device *d*, for instance such as is described in U. S. Patent No. 1,627,037. By this device *d* the bundle of fibers is opened up and, if desired with the use of a second watering trough is spread 45 in the form of a sliver uniformly on the whole working breadth of the conveyer band *e*. In Fig. 1, for the sake of simplicity, only one conveyer band with the necessary appendages is shown for the whole after-treatment. The conveyer band is permeable for liquid and consists 50 either of perforated or woven material resistant to chemicals. The band is endless and runs on the rollers *f*, *f*₁, which drive it. Between the rollers *f*, *f*₁ the band is carried either on a perforated table or, as shown in Fig. 1, on rollers *g* which are preferably driven. Above the band 55 there are arranged troughs supplied continuously with the chemicals necessary for the after-treatment and liquids for washing, for instance at *h* washing occurs, at *i* treatment with sulfite, at *k* a second washing, at *l* a treatment with hydrochloric acid, at *m* a third washing and at *n* the treatment with soap solution. At the discharge end of the conveyer the excess of 60 liquid is expressed by a roller *o* in cooperation with the conveyer roller *f*₁. The several liquids used in the treatment run away into receptacles, not shown in the drawings.

It is important that the sliver should maintain 70 its position during the wet treatment and should not be broken up by the water jets in a transverse direction. Therefore, on the upper face of the conveyer band a guide *p* is arranged which may consist of either stationary strips against 75 which the sliver slides with the smallest pos-

sible amount of friction, or walls travelling with the band, such walls being constructed, for example, of chains with corresponding chain wheels.

In Fig. 2 is shown a similar apparatus in which the conveyer band is subdivided, the separate bands *e*, *e*₁, *e*₂, etc., being preferably inclined, so that owing to back flow of the treating liquids against the direction of travel of the bands the liquids are better used. Short transfer bands *s*, *s*₁, etc., bridge the distance between one conveyer and the next. These may be perforated and in order to avoid, as far as possible, the transfer of liquid from one conveyer to the next expressing rollers *o*, *o*₁, *o*₂, etc., co-operate 15 with the conveyer rollers *f*, *f*₁, *f*₂, etc.

In Fig. 3 a modified apparatus for working up the sliver collected on the conveyer band is shown. In this arrangement the squeezing rollers *o*₂ are mounted above the conveyer band *e*. The guide *p* of the conveyer band shown in Fig. 1 has been omitted as being unnecessary if the band is large enough. Below the squeezing roller there are arranged channels *t* which guide the squeezed liquid into the collecting troughs *u* arranged between the upper and lower part of the conveyer band. The sliver is passed on a separate conveyer band for the treatment with soap because in this case nickel wire gauze is used.

Fig. 4 shows an arrangement in which a smooth squeezing roller is arranged above a grooved roller. The sliver is squeezed between the two rollers and the liquid flowing off is guided in a collecting vessel by means of a channel arranged below the squeezing rollers. Between the upper and the lower part of the conveyer band a roof-shaped distribution plate is arranged which distributes the liquid flowing during the treatment through the upper part of the conveyer band so that it passes over the lower 40 part of the band and flows directly into the collecting vessel.

In Fig. 5 is shown how the band is squeezed once more in the middle between the squeezing rollers arranged at the end of each treatment. 45

Fig. 6 shows an arrangement similar to that shown in Fig. 2 with the difference that the squeezing rollers are mounted so that the band is not pressed by them. After the sliver has been pressed it falls back on the next conveyer 50 band.

Fig. 7 shows a roller provided with bosses. This roller may be arranged so as to co-operate with one of the supporting rollers as shown in Fig. 3. By this roller the sliver receives a profile 55 as a consequence of which the lower strata of the sliver are more intensely treated. Such an improved treatment of the lower strata of the sliver may also be attained by arranging suitable spraying devices in the way of the sliver, 60 for instance, such as are shown in Figs. 8 and 9. According to Fig. 8 a guide roller may be arranged in the path of the sliver and near the guide roller there are arranged perforated tubes by which the treating liquid 65 can be sprayed on the lower side of the sliver which is lifted for passing over the guide roller. According to Fig. 9 the sliver is guided over a hollow perforated roller which is driven so that it has a peripheral velocity equal to the 70 speed at which the sliver advances. In the hollow roller a perforated tube is mounted for spraying liquid through the hollow roller against the lower side of the sliver whereby the effect of the treating liquid is considerably increased. 75

Such a hollow roller with a perforated tube mounted inside is shown in Fig. 6 as assisting the washing effect before the sliver is treated with the soap solution.

5 The finished after-treated and squeezed sliver, in which the individual fibriles have not varied or have very little varied from their original relative position, is either wound to a roll indicated by *r* in the drawings or conducted continuously and directly to a mechanical drying device, not shown in the drawings.

10 After the drying or after the adjustment of the degree of moisture, the artificial fibers, after they have been opened, show a surprising capacity for spinning.

15 The process and the apparatus may be used in the manufacture of all wet spun artificial fibers, for instance artificial fibers from ammoniacal copper oxide solution; in the case of copper fiber it is important that the fibers should be cut or torn before the final conversion into cellulose.

What we claim is:

20 1. An apparatus for the continuous production of curled rayon staple fibers comprising a cutting device capable of cutting a bundle or sliver of continuous rayon filaments, attached thereto a device capable of loosening the staple fiber cuttings and of forming a continuous fleece 25 of fibers, a perforated conveyer band operatively connected therewith so as to receive and forward the continuous fleece, a number of sprinklers mounted above said conveyer band to soak said fleece with a plurality of treating and washing liquids, and squeezing rollers arranged above said conveyer band and between the particular 30 sprinkling devices.

2. An apparatus for the continuous production of curled rayon staple fibers comprising a cutting device capable of cutting a bundle or sliver of continuous rayon filaments, attached thereto a device capable of loosening the staple fiber cuttings and of forming a continuous fleece 5 of fibers, a perforated conveyer band operatively connected therewith so as to receive and forward the continuous fleece, said perforated conveyer band being slightly inclined to the vertical and mounted on rollers, a number of sprinklers mounted above said conveyer band to soak said fleece with a plurality of treating and washing liquids, and squeezing rollers arranged above 10 said conveyer band and between the particular 15 sprinkling devices.

3. An apparatus for the continuous production of curled rayon staple fibers comprising a cutting device capable of cutting a bundle or sliver of continuous rayon filaments, attached 20 thereto a device capable of loosening the staple fiber cuttings and of forming a continuous fleece of fibers, a perforated conveyer band operatively connected therewith so as to receive and forward the continuous fleece, a number of 25 sprinklers mounted above said conveyer band to soak said fleece with a plurality of treating and washing liquids, squeezing rollers arranged above said conveyer band and between the particular 30 sprinkling devices and guiding rollers arranged on said conveyer band.
